DEVICE FOR SUPPORTING BINOCULARS ON
MILITARY HEADGEAR

Martin Glover Larrabee, Philadelphia, Pa., and Arthur J. Rawson, Frederick, Md., assignors to the United States of America as represented by the Secretary of the Air Force

Application December 8, 1948, Serial No. 64,102

6 Claims. (Cl. 83—36)

1

The invention described herein may be manufactured and used by or for the Government for governmental purposes without payment to us of any royalty thereon.

This invention relates to a device for supporting a binocular or the like upon military headgear, especially upon combat helmets or liners thereof.

Among the objects of the invention are the provisions of a device of this character which may be snapped over the edge of the helmet brim at three points or more and tightened thereon.

Another object is to provide a binocular support which has three adjustments for aligning the binocular with the wearer's eyes, namely, (a) an interpupillary-distance control, (b) an instrument-height control, (c) a line-of-sight control to align the binocular with the normal line-of-sight of the user.

Another object is to provide a power-pack support positioned to counterbalance together with the weight of the power pack the weight of the instrument and its adjusting means. A power pack or its support is necessary only when an infra-red-sensitive binocular for night vision is used. Consequently the power-pack support may be omitted.

In the drawings:

Fig. 1 is a perspective view of the support taken from an oblique front position below the general level of the device. The binocular and power-pack are indicated by dashed lines.

Fig. 2 is a side elevation partly in section of the front part of the device taken from a position at right angles to the major axis and level therewith.

Fig. 3 is a rear elevation of the interpupillary-distance adjustment and is taken on the line 3—3 of Fig. 2.

Fig. 4 is a plan view of a fragment of the structure seen in Fig. 3.

Fig. 5 is a plan view showing the binocular in dashed lines, as mounted on the device.

Referring especially to Figs. 1 and 5, 10 is an oval metallic headband to which are attached a sufficient number of spring clips 11 to enable the device to be firmly attached to a helmet or liner by the brim thereof. Attached by rearwardly projecting antivibration hinges 12 at the rear of band 10, there is a battery support 13 of parallelogram shape made from metal strap-ping. Attached by pivots 14 at points of approximately half way between front and rear of the band 10 there is an auxiliary half oval band 15 which may be raised and lowered to

2

accommodate the binocular to the wearer's eye level.

Adjustment of the band 15 is accomplished by means of a vertical screw 16 which operates 5 through a pivoted bearing 17 carried adjacent the front of band 15 and which abuts a stop 18 carried on the front of band 10. The bearing 17 extends through an outwardly inclined backing board or plate 19 which may be made of pressed fiber or other stiff organic material. It is mounted on the band 15 and carries an angled portion 20 through which the bearing 17 extends.

The function of the backing board 19 is to furnish a fulcrum against which a clamping plate 21 may be supported and adjusted. The clamping plate 21 is approximately as high as the backing plate 19 but is considerably wider (see Fig. 5). An adjusting screw 23 extends through the clamping plate 21 and abuts backing plate 19, thereby permitting the verticality of the clamping plate 21 to be adjusted. A hinge 24 between the two plates at substantially their lowest points cooperates with the screw 23 in providing the adjustment. Coil springs 25 (see Fig. 5) extend from anchorages 26 on frame 10 to other anchorages 27 at the top of clamping plate 21 to hold the latter firmly against the backing board 19 to as great an extent as the adjustment of screw 23 permits.

While ordinary binoculars need no interpupillary adjustment other than the one customarily built into them, the special infra-red-sensitive binoculars used in warfare do require one built into their support. Figs. 2, 3 and 4 show the construction of this adjustment especially clearly. Behind the clamping plate 21 there are pivoted by bolts 28 and 29, a pair of wings 30 and 31 upon the outer ends of which are mounted lugs 32 and 33, respectively, to which the binocular 35 is attachable by bands and screws (not shown). Attachment is made close to the outer ends of the binocular near the objective lens.

The wings 30 and 31 are preferably thinned at their inner ends to about half their thickness 45 at their outer ends. They are overlapped at their inner ends as can be seen in Figs. 2 and 3. A screw 34 is mounted at the top of clamping board 21 through a flange 35 provided for the purpose, to press upon the overlapped wing inner ends to pivot the wings 30 and 31 about the bolts 28 and 29, respectively. This rotational motion has the effect of bringing the objective lenses of the binocular slightly closer together and of increasing the interpupillary distance between the ocular lenses. A pair of coil

springs 36 and 37 anchored to the lower end of the clamping board 21 are provided to pull the wings 28 and 29 to horizontal again after the compression of screw 34 is relaxed.

Operation

The operation of the binocular mount will be readily understood by optical scientists, technicians and others merely by inspecting the accompanying drawings. However, it may be stated that each barrel of the binocular is attached to the mount by screws extending through the respective lugs 33. The angle of attachment, in the case of an infra-red-sensitive binocular is such that the oculars are at approximately interpupillary distance while the objectives are widely spread apart. The adjusting screw 34 is turned down to increase the interpupillary distance and backed off to decrease it. The springs 36-37 furnish the necessary tension for the latter operation. Screw 16 is turned down to raise the line of sight and backed off to decrease its inclination. If it is desired to look at objects in the wearer's foreground adjusting screw 23 is turned inward against the tension of springs 25 to give the clamping plate 21 a slight downward inclination, as much as desired. To examine the distant background, the clamping plate 21 is kept vertical or nearly so. To examine the sky, the screw 23 is backed off considerably.

By manually grasping the power-pack carrier 13 and altering its angle to the wearer's head by pivoting the carrier about the stiff hinges 12, an angle that is comfortable to the wearer and efficient for counterweighting the binocular can be achieved. Once set, the hinges 12 are stiff enough that the ordinary jog of the wearer's walking or running pace will not alter their setting, thereby preventing the carrier and pack from contacting the wearer's head and neck.

We claim as our invention:

1. In a device for supporting a binocular or the like on military headgear or the like, a band adapted to encircle the crown of said headgear, spring clips attached to said band for engaging the brim of said headgear by the edge thereof, a semicircular band pivoted to the first band, so as to be vertically adjustable in relation to the frontal area of the wearer's head to vary the height of the binocular, a backing board depending from the front of said second band and rigidly held thereto, a clamping plate hingedly attached to the bottom of said backing board and folded upwardly to form an acute angle with said backing board, wings attached to said clamping plate, means for attaching one barrel of a binocular to the outer end of each wing, means for regulating the forward inclination of said clamping plate in respect to said backing board to provide a line-of-sight control, and means for adjusting the inclination of said wings through a limited up or down rotation thereof in respect to the clamping plate to vary the interpupillary distance of the binocular, and a plurality of coil springs positioned between said clamping plate and said first band and between said clamping plate at the lower end thereof and the outer ends of said wings and tensioned to return the adjustable band, clamping plate and wings to their respective zero positions after the force producing their respective adjustment is relaxed.

2. In combination in a binocular support a first band encircling the wearer's head, a second band pivoted at two points, one on each side of the band, said points being approximately over the wearer's ears, a lug attached to the front

of the first band, and adjusting screw pivotally mounted at the front of the second band and capable of contacting said lug, a backing board attached to said second band at the front thereof and depending therefrom a clamping board capable of supporting a binocular, means for hingedly attaching said clamping board to said backing board substantially at the lowest point of both, coil spring means anchored on the first band tensionally holding the top of said clamping board toward said backing board and an adjusting screw extending through at least one of said boards and contacting the other to adjustably space them apart in angular relation to the hinged attaching means.

3. In a binocular support, a headband, a half-oval band pivotable on said first band at two points approximately equidistant from the front and rear of said first band, a lug at the front of said first band, a backing board attached to the front of said half-oval band, a pivotally mounted height adjusting screw threadedly adjustable to control said half oval band and abutting lug whereby the angle between said bands may be varied by turning said screw, said screw being mounted through said backing board where said board is attached to said band, a clamping plate mounted in front of said backing board, a hinge between the lower end of said clamping plate and backing board, coil spring means mounted on said headband and on said clamping plate to pull said clamping plate toward said headband, an adjusting screw between said backing board and through said clamping plate for adjusting the angular distance therebetween, an inwardly extending flange at the top of said clamping plate, a pair of wings extending outwardly from said clamping plate and pivoted thereto at a point intermediate of their ends, said wings having overlapping thinned inner ends, means at the outer ends of the wings for attaching one barrel of a binocular to each wing, an adjusting screw extending downward through said flange to press downwardly on said inner wing ends to pivot the wings upwardly at their outer ends and coil springs mounted and tensioned between the lower end of said clamping plate and each wing so that said wings will be pulled down when the pressure exerted by the wing adjusting screw is relaxed.

4. In combination in a support for an infra-red-sensitive binocular, a band for encircling the crown of the wearer's military helmet, spring clips attached to said bands and depending therefrom for snapping onto the brim edge of said helmet, a second band pivoted at two points to said first band, the second band being vertically adjustable over the wearer's forehead, means mounted on the front of said second band including a winged clamping plate of horizontally variable dimension and a backing plate in angularly adjustable relation for holding and adjusting an infra-red-sensitive binocular to the requirements of the individual wearer's eyesight and a power pack support comprising a metal strap bent to rectangular shape and mounted at the rear of the first band, stiff hinges for adjustably mounting said support, said support when filled with a power pack being adapted to supply said binocular with electrical energy and to counterbalance the combined weight of the binocular and its adjusting means and to prevent undesired contacts of the power pack with the wearer's neck or the rear of his head.

5. In a binocular support, means including a band for encircling the crown of a military hel-

75

met, clip means for attaching the band to the brim of said helmet, a semicircular band pivoted at two points to said first band and movable to pivot upon said points so as to be adjustable up and down over the forehead of the wearer, means including a winged, forwardly positioned clamping plate of horizontally variable dimension and a rearwardly positioned backing plate in angularly adjustable relation to each other on the front of said semicircular band for adjustably supporting a binocular for line-of-sight adjustment relative to the wearer's eyes and in angular relation to the first band and a power pack carrier made of strap-like material attached to the rear of the first band whereby to contribute to counterbalancing the weight of the binocular supporting means.

6. In the combination set forth in claim 5 a pair of rearwardly projecting stiff hinges attaching the power pack carrier to the rear of the first band whereby the carrier may be angu-

larly pivoted in relation to said band and held away from the wearer's head and neck.
